(57) CLAIM

We claim the ornamental design for a switch lockout device, as shown and described.

DESCRIPTION

FIG. 1 is an upper perspective view of the switch lockout device, shown with the cover in the open position;

FIG. 2 is a lower perspective view thereof;

FIG. 3 is a top plan view thereof;

FIG. 4 is a right side elevational view thereof;

FIG. 5 is a left side elevational view thereof;

FIG. 6 is a bottom plan view thereof;

FIG. 7 is a front elevational view thereof; and,

FIG. 8 is a rear elevational view thereof.

The portions of the switch lockout device in broken lines are for illustrative purpose only and form no part of the claimed design.
